UNITED STATES PATENT OFFICE.

PERRY OSCAR HELLER, OF PROPHETSTOWN, ILLINOIS.

STRAINER.

Application filed February 28, 1923. Serial No. 621,827.

To all whom it may concern:

Be it known that I, PERRY O. HELLER, a citizen of the United States, residing at Prophetstown, in the county of Whiteside 5 and State of Illinois, have invented new and useful Improvements in Strainers, of which the following is a specification.

This invention relates to strainers for removing impurities and foreign matter 10 from milk or other liquids.

The object is to provide straining means for this purpose which may be applied to bottles, cans or other receptacles having their necks provided with the necessary threads 15 and of the proper diameter, all of the parts of the strainer being separably held to the mouth of the receptacle in such manner as to prevent accidental displacement and to force the contents to pass through the straining medium without leakage around the 20 edges thereof.

Another object is to provide a strainer which may be easily removed from its position to replace absorbent cotton or other 25 fibrous material used in the device, when the same has become saturated or clogged with accumulations, and to cleanse all the parts of the strainer in order to maintain the same in a sanitary condition.

30 A full and complete understanding of the invention may be obtained from a consideration of the following detailed description, taken in connection with the accompanying drawing forming a part of this specification; it being understood that while the drawing shows a practical form of the invention, the latter is not confined to strict conformity with the showing thereof, but may be changed or modified, so long as such changes or modifications mark no material departure 35 from the salient features of the invention, as specifically pointed out in the appended claims.

40 Referring to the drawings, in which similar reference characters designate corresponding parts throughout the several figures:—

Fig. 1 is an inverted, longitudinal section through the mouth of a receptacle having the improved strainer applied thereto.

Fig. 2 is a horizontal sectional view, taken on the line 2—2 of Fig. 1, and looking in the direction indicated by the arrows.

Fig. 3 is a top plan view of the perforated cap.

While the improved strainer has been

shown in the drawing, as applied to the mouth of a glass or porcelain receptacle in the form of a bottle or jar, it is to be understood that the same may be used in connection with an ordinary metal milk can, or any other similar receptacle, where it is desired to strain or filter liquid of any kind capable of being freed of foreign matter or accumulations in this manner.

In the drawing, there is illustrated a portion of a jar or bottle 1, which may be formed of any suitable material and having its open end cut off square, as at 2, to provide a mouth, and also to act as a bearing surface for the reception of the straining elements. This flat surface 2 in the event the device is used on a metal can, may be formed by an inturned flange, as will be easily understood.

The outer surface of the reduced neck portion 3 of the receptacle, is provided with threads 4, formed in an appropriate manner depending on the material comprising the receptacle, said threads extending substantially one-half the length of the neck.

Adapted to be threaded onto the neck of the receptacle, is a metallic cap 5 formed of some noncorrosive metal, and comprising a flat cover plate 6 having its peripheral margin formed into an integral, threaded flange 7 of substantially equal height with the height of the threads on the neck of the bottle, the marginal edge of the flange being rolled into a strengthening bead 8 to prevent distortion of the same.

The flat cover 6 is provided throughout its area with a plurality of perforations 9, with the exception of a continuous imperforate margin 10 located adjacent to the flange 7, which has its outer face fluted, as at 11, between the base of the flange and the beginning of the threads thereon, for facilitating the turning on or off of the cap in the usual manner.

A wire gauze strainer 12 formed of suitable non-corrosive material, and made circular to correspond in diameter, with the outer edge of the flat surface 2 at the mouth of the bottle, is adapted to rest on said flat surface, and has its outer end embedded in a lead or solder ring 13 to prevent unraveling of the wire fabric and undue distortion of the same.

Upon the outer face of the circular gauze strainer 12 there is placed a round layer of absorbent cotton 14, or other similar mate-

rial, capable of arresting and holding the smaller particles or impurities. The cap 5 is then applied to the mouth of the receptacle and screwed tightly thereon, when the 5 imperforate margin 10 clamps and compresses the absorbent material between the same and the flat end of the neck of the receptacle, the gauze being interposed therebetween. By this arrangement, the outer 10 edges of the gauze and cotton provide a gasket between the outer edge of the neck and the top or cover.

With this arrangement, it will be seen that it is impossible for any of the contents 15 of the receptacle to pass around the marginal edge of the absorbent material, but is forced to pass straight through the same, the wire gauze arresting the larger particles and sustaining the absorbent material from 20 the inside, while the cover plate 6 of the cap supports the said material on the outside and allows the flow of the liquid contents from the container without interference.

The fiber of the cotton or other material 25 is thus held in position for the perforated portion of the cap on one side and the screen on the other, thus avoiding the formation of channels or gulleys through the cotton by the flow of the liquid, as the said 30 fibers can not move nor be forced apart to form such openings.

From the foregoing it will be seen that a simple, cheaply manufactured, sanitary filter or strainer has been provided for straining 35 milk or other liquids and which may be readily applied in position on the mouth

of a bottle, jar, can or other receptacle, and that the same may be readily removed therefrom for the purpose of cleansing the same or for replacing the absorbent material, 40 every part of the strainer being capable of thorough cleansing.

What is claimed is:—

In combination with a receptacle having an exteriorly threaded neck, with the open 45 end of the neck flat, a circular gauze disc bearing against the flat end of the neck and extending to the outer edge thereof, a circular layer of absorbent material placed over the gauze disc and extending to the outer 50 edge thereof, and a detachable cap having a peripheral threaded inturned flange for engagement with the neck of the receptacle to clamp the outer edges of both the gauze disc and absorbent material to the flat open 55 end of the neck, said cap having its cover plate perforated except around the margin where it is opposed to the flat end of said neck, whereby the imperforate portion of the cover plate engages and holds the outer 60 edges of the gauze disc and the cotton against the end of the neck, said disk and absorbent material forming a gasket between the neck and the imperforate portion of the cap so as to prevent the liquid contents from passing around the marginal edges of said disk and absorbent material.

In testimony, that I claim the foregoing as my own, I have hereto affixed my signature.

PERRY OSCAR HELLER.
